UNITED STATES PATENT OFFICE

BRUNO M. SMITH, OF WEST ORANGE, AND CHARLES W. DANN, OF EAST ORANGE, NEW JERSEY, ASSIGNORS TO THOMAS A. EDISON, INCORPORATED, OF WEST ORANGE, NEW JERSEY, A CORPORATION OF NEW JERSEY

DESIGN FOR A SUGAR POT OR LIKE ARTICLE

Application filed August 6, 1930. Serial No. 36,582. Term of patent 14 years.

To all whom it may concern:

Be it known that we, BRUNO M. SMITH, a citizen of the United States, and a resident of West Orange, in the county of Essex and State of New Jersey, and CHARLES W. DANN, a citizen of Germany, and a resident of East Orange, in the county of Essex and State of New Jersey, have invented a new, original, and ornamental Design for Sugar Pot or like Article, of which the following is a specification, reference being had to the accompanying drawing, forming a part thereof.

In the drawing:

The single figure is a perspective view of a sugar pot or like article showing our new design.

We claim:

The ornamental design for a sugar pot or like article, substantially as shown.

BRUNO M. SMITH.
CHARLES W. DANN.
